UNITED STATES PATENT OFFICE.

DAVID C. PRINCE, OF SCHENECTADY, NEW YORK, ASSIGNOR TO GENERAL ELECTRIC COMPANY, A CORPORATION OF NEW YORK.

VACUUM-TUBE CIRCUITS.

Application filed November 9, 1922, Serial No. 599,919. Renewed October 27, 1927.

My present invention relates to vacuum tube circuits, and more particularly to circuits employed with vacuum tubes for producing alternating currents from direct currents.

It has been recognized that for efficient operation of a thermionic vacuum tube device as a rectifier, the tube losses should be made as small as possible and that this result may best be accomplished by so arranging the circuit that a nearly constant current will flow for a considerable fraction of a cycle, the current rising quickly from zero to that value, then remaining constant and quickly falling to zero again. The tube loss which is the product of current by the voltage drop across the tube at any instant will then be a minimum.

In employing thermionic vacuum tubes for converting direct current to alternating, however, it has not been possible to obtain such high efficiency because of the fact that the voltage drop across the tube has been sinusoidal and hence the potential drop has been a minimum at only one instant during the cycle. At all other instants it has been higher and additional losses have resulted.

The object of my present invention is to provide circuit arrangements whereby the difficulty mentioned may be largely avoided and the principal losses will be those due to space charge, filament excitation and control, and these losses may be reduced to the minimum necessary to make the tube conduct current for the necessary fraction of a cycle.

The novel features which I believe to be characteristic of my invention are set forth with particularity in the appended claims. My invention itself, however, both as to its organization and method of operation will best be understood by reference to the following description taken in connection with the accompanying drawings in which Figs. 1 to 3 inclusive, show diagrammatically as many different circuit arrangements whereby my invention may be carried into effect.

In the arrangement shown in Fig. 1, two three-electrode vacuum tubes 1 and 2 are indicated. The plate circuits of these tubes include condenser 3 and inductance 4, energy being supplied for the operation of the plate circuits from a direct current source 6 connected to the mid point of inductance 4,

through an inductance 5 which maintains the current supplied to the tubes substantially constant. The grid or control circuits of the tubes include an inductance 7. A common portion of the two grid circuits contains an inductance 9 and a resistance 10. The circuit to which alternating current is to be supplied may be connected to inductance 8, which is coupled to inductance 4.

Control excitation for the grids of the tubes is obtained from a separate oscillating vacuum tube 12. The plate of tube 12 is connected through inductance 13 with the direct current source 6. The grid circuit contains an inductance 14, which is coupled to inductance 13, and the usual grid condenser 15 and grid leak 16. Inductances 13 and 14 are both coupled to inductance 7 which with condenser 11 is the frequency determining element of the separate source.

In the circuit arrangement shown in Fig. 2 self excitation of the tubes 1 and 2 is obtained by means of the two inductance coils 17 and 18 which are included in the grid circuits. Both of these coils are coupled to inductances 4, and coil 18 has a parallel condenser 19. Inductance 18 and condenser 19 are proportioned to resonate at the same frequency as inductance 4 and condenser 3. The drops across inductances 17 and 18 are, therefore in quadrature.

In Fig. 3 I have shown a circuit organization similar to those described, but arranged to produce three-phase current. In this case, three tubes 22, 23 and 24 are employed. The plates of these tubes are connected through inductances 27, 28 and 29 to choke inductance 25 through which energy is fed from the direct current source 26. Inductances 30, 31, 32 are inductively related to 27, 28 and 29 respectively. These inductances are connected in delta and supply energy to a load such, for example, as a synchronous motor 44, which is also the frequency determining element. Inductances 27, 28, 29, 30, 31 and 32 may be iron cored transformers where the frequency is relatively low. Grid excitation is supplied from an assemblage of inductances 33, 34, 35 and 36, 37, 38 arranged similarly to 27 to 32 inclusive. The individual grids are fed through ballast resistances 41, 42, 43. The neutral points of inductances 36, 37 and 38 are connected to the negative generator

terminal through resistance 40 and inductance 39. Inductances 33, 34 and 35 are fed from 30, 31, 32 in such a way that the phase of the grid control potentials can be varied.

5 To understand the operation of these circuits consider the operation of Fig. 1 as a rectifier, that is with the grids and their connections removed. The impressed voltage is sinusoidal. This voltage is communicated by inductance 8 to inductance 4 and by it to the plates. The output is delivered to the generator 6, which now acts as an energy absorbing device through inductance 5, which maintains the current constant. Now 10 at constant current the drops across both tubes and energy absorbing device are constant, therefore the difference between the sinusoidal impressed voltage and the constant delivery voltage appears as drop across 15 the inductance 5 and does not occasion loss.

To secure analogous operation it is necessary to observe that while the grid is positive a rough proportionality exists between grid and plate currents. The grids are 20 therefore connected in a manner precisely similar to the plates being excited by inductance 7 and delivering rectified current to load resistance 10 through inductance 9, which maintains the current constant. The 25 grid and plate circuits are now cooperating to deliver constant direct current from sinusoidal alternating current with minimum loss. To reverse the direction of energy flow it is only necessary to reverse the 30 plate excitation 180° in phase and raise and reverse the potential of generator 6. Inductance 8 then automatically becomes an 35 output instead of an input circuit. The losses have not been changed by this maneuver 40 because during the portions of the cycle when current flows the conditions have not been changed while a cessation of grid current in one tube indicates that the grid has 45 become negative with respect to the filament so that the plate current is cut off. With the arrangement shown in Fig. 2, then, current flows from each grid and each plate substantially half the time, and during that half the tube drops are held constant by the 50 inductances 9 and 5 respectively. This gives the maximum output per tube and maximum efficiency obtainable with a given design of tube. During the period when 55 current must be transferred from tube 1 to tube 2 there is a rapid change of current in the circuit. In the plate circuit this rapid change can take place in condenser 3 where it will set up no great voltage. At higher frequencies the condenser 11 of Fig. 1 provides 60 a similar path for rapidly changing grid currents. When the frequency is high even the inductance of leads begins to cause the current transfer in the grid circuit to lag behind the voltage. It is necessary to 65 compensate for this lag and for the corresponding

lag in the plate circuit. With a separate source of grid excitation as shown in Fig. 1, and proper adjustment of the resonant circuits the phases will automatically take up their proper relative positions.

70

Fig. 2 shows an alternative method of securing phase angle correction. The grid excitation inductance has been divided into two sections 17 and 18. Inductance 18 is tuned by condenser 19. The voltage induced 75 in each of these inductances by the current in inductance 4 is in quadrature with the current. Since inductance 18 and condenser 19 tune they act together like a noninductive resistance. The current in this circuit is 80 therefore in phase with the voltage and in quadrature with the current in inductance 4. The self induced voltage in inductance 18 is in quadrature with the current in it and therefore the induced voltage in inductance 17 and the self-induced voltage in inductance 18 are in quadrature and any desired phase angle can be obtained by their proper combination.

85

Fig. 3 is based on the same principles as 90 the preceding figures except that instead of the current flowing at any one time in one of two tubes it flows in one of three. The resultant output is therefore three-phase. With polyphase output any desired phase 95 angle can be secured for excitation. This is done by the variable taps by which inductances 33, 34 and 35 are excited from 30, 31 and 32. Additional grid resistances 41, 42 and 43 may be found advantageous in 100 some instances to accelerate the current transfer from one grid to the succeeding. The maintenance of symmetrical three-phase relationships is dependent upon balance in the element which determines the 105 frequency and load.

100

Where it is important to minimize harmonics in the alternating current circuits two or more sets of single or three phase circuits may be associated with the same 110 primary inductances 30 to 35, inclusive. In this way any undesirable harmonics can be eliminated.

110

Certain features of the present application are disclosed and claimed in my co-pending application Serial No. 636,696, filed May 4, 1923, and assigned to the same assignee as the present application.

115

What I claim as new and desire to secure by Letters Patent of the United States, is:— 120

1. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, means for maintaining substantially constant the flow of current to the grid circuits, and means for permit- 125

130

- ting of the ready transfer of the exciting current from the grid circuit of one device to the grid circuit of another device.
2. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, means for varying the excitation of the different grids to cause current to flow in the different plate circuits at different intervals, means for maintaining substantially constant the flow of current to the grid circuits, and means for permitting the ready transfer of the exciting current from the grid circuit of one device to the grid circuit of another device.
3. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, an inductance of suitable value which is common to all of the grid circuits for maintaining substantially constant the flow of current to the grid circuits, and means for permitting of the ready transfer of the exciting current from the grid circuit of one device to the grid circuit of another device.
4. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, means for varying the excitation of the different grids to cause current to flow in the different plate circuits at different intervals, means for permitting of the ready transfer of the exciting current from the grid circuit of one device to the grid circuit of another device, and an inductance of suitable value which is common to all of the grid circuits for maintaining substantially constant the flow of current to the grid circuits.
5. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, means for adjusting the phase of the currents supplied to the grid circuits, and means for maintaining substantially constant the flow of current to the grid circuits.
6. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, means for varying the excitation of the different grids to cause current to flow in the different plate circuits at different intervals, means for adjusting the phase of the currents supplied to the grid circuits, and means for maintaining substantially constant the flow of current to the grid circuits.
7. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, an inductance of suitable value which is common to all of the grid circuits for maintaining substantially constant the flow of current to the grid circuits, and means for adjusting the phase of the currents supplied to the grid circuits.
8. A system for generating oscillations comprising a plurality of electron discharge devices having plate and grid circuits, a source of direct current for exciting the plate circuits, means for maintaining substantially constant the current supplied by said source, means for impressing an alternating current upon the grid circuits, means for adjusting the phase of the current supplied to the grid circuits, means for varying the excitation of the different grids to cause current to flow in the different plate circuits at different intervals, and an inductance of suitable value which is common to all of the grid circuits for maintaining substantially constant the flow of current to the grid circuits.
9. The combination in a system for producing polyphase alternating current from direct current of a plurality of electron discharge devices having plate and grid circuits, a source of direct current for exciting the plate circuits, inductances in the plate circuits which form the primary windings of a polyphase transformer, inductances in the grid circuits which form the secondary windings of a second polyphase transformer and adjustable taps connected to the secondary winding of the first transformer from the primary windings of the second transformer whereby polyphase currents of a desired phase may be supplied to the primary winding of the second transformer.

In witness whereof, I have hereunto set my hand this 8th day of November, 1922.

DAVID C. PRINCE.
